ELECTRONIC VALVE APPARATUS SUITABLE
FOR USE IN COUNTING ELECTRICAL IM-
PULSES

Thomas Harold Flowers, London, England

Application November 20, 1945, Serial No. 629,856
In Great Britain November 17, 1944Section 1, Public Law 690, August 8, 1946
Patent expires November 17, 1964

4 Claims. (Cl. 250—27)

1

This invention relates to electronic valve apparatus which is suitable for use in counting electrical impulses.

In known apparatus for counting electrical impulses a number of electronic valves have been arranged in ring formation, being interconnected in such manner that each valve in turn becomes non-conducting while the remainder of the valves in the ring formation are conducting. This condition of conducting and non-conducting valves is a stable condition that is, the electron flow in each valve is unchanged until an electrical impulse is impressed on the input of the apparatus whereupon the non-conducting valve becomes conducting, and one of the other valves in the formation becomes non-conducting. The term stable condition of electron flow in this usage includes the case when a valve is non-conducting.

In the known apparatus the attainment of the stable conditions, in number equal to the number of valves in the ring formation, has been mainly accomplished by applying to the grid of each valve, direct current voltages derived from an electrode, usually the anode, of the other valves of the formation, each grid being connected to all the other valves through suitable resistances. The selection of a different valve to be non-conducting and the production of a different stable condition was effected by applying a transient voltage or voltage impulse to the same grid of the next valve to be made non-conducting as the grid to which the direct current voltages are applied, this voltage impulse being obtained by feeding back through a condenser a portion of the voltage change of one electrode, usually the anode, of each valve in the ring formation to the said grid of the said next valve.

In the known apparatus the changing from one stable condition to another, i. e. the selection of a different valve to be non-conducting, has been uncertain and the operation of the apparatus consequently impaired. It is an object of this invention to provide apparatus of the kind referred to in which the change from one stable condition to another is made more certain when an electrical impulse is applied to the input. It is a further object of the invention to provide electrical impulse counting apparatus which is more reliable and accurate than has been hitherto possible.

The invention, accordingly, provides electronic valve apparatus adapted in response to electrical impulses received at its input, to produce at its output electrical impulses which are lower in number than and are in pre-determined numeri-

2

cal relation with the number of received impulses and having a number of valves interconnected in a ring formation such that each valve in turn is caused to attain a stable condition of electron flow which is different from that of the other valves in the formation wherein the valves are of the multi-grid type and the attainment of the stable conditions of electron flow in the various valves is determined by means arranged to apply to a grid of each valve direct current voltages derived from the circuits of the other valves of the ring formation and wherein the selection of each valve in turn to attain said different condition of electron flow is effected by means arranged to apply a transient voltage or voltage impulse to a grid of the valve required to be selected other than the grid to which the said direct current voltages are applied.

The invention will be described, by way of example, with reference to the accompanying drawing which shows a diagrammatic arrangement of apparatus arranged as a scale-of-three counting device.

For convenience, the application of the steady direct current voltages in the manner referred to is termed D. C. feed-back and the application of a transient voltage or a voltage impulse is termed A. C. feed-back.

Referring to the accompanying drawing, valves 1, 2 and 3 are multi-grid valves of the pentode type arranged to form a ring of three elements.

The cathodes of these valves are connected to earth and their anodes are connected via resistors 11, 21, 31 respectively to the positive terminal of a battery V1, the negative terminal of the battery being connected to earth. The D. C. feed-back to valve 1 is provided via resistor 12 which connects the anode of valve 2 and resistor 13 which connects the anode of valve 3 to the control grid of valve 1 via the grid resistor 14. Similarly the resistors 22 and 23 connect the anodes of valves 3 and 1 respectively to the control grid of valve 2 via grid resistor 24, and resistors 32 and 33 connect the anodes of valves 1 and 2 respectively to the control grid of valve 3 via grid resistor 34. The voltage changes due to the D. C. feed-backs are brought to suitable points on the grid-voltage anodes-current characteristics of valves 1, 2 and 3 by the negative voltage from battery V2 connected via resistors 15, 25, 35 respectively to the common connections of the D. C. feed-back resistors 12, 13 for valve 1, 22, 23 for valve 2, and 32, 33 for valve 3. The A. C. feed-back to valve 1 is applied by connecting the anode of valve 3 via condenser 16 in

series with resistor 17 to the suppressor grid of valve 1 which is further connected via resistor 18 to earth. Only a portion of the anode voltage change or voltage impulse of valve 3 is thus fed back to the suppressor grid of valve 1. If the whole or too great a portion is fed back the circuit tends to oscillate continuously. The A. C. feed-back to valves 2 and 3 can be similarly traced via condenser 26 and resistors 27, 28 for valve 2 and condenser 36 and resistors 37 and 38 for valve 3. The screen grid of valve 1 is joined to the positive of battery VI via resistor 19. The screen grids of valves 2 and 3 are similarly joined via resistors 29 and 39 respectively.

Impulses to drive the apparatus are applied to the input of the apparatus via lead L1. Valve 4 is arranged with its cathode joined via resistor 41 to earth, its anode connected to the positive of battery VI and its grid biased negatively by resistors 42 and 43, and with condenser 44 interposed between the grid and the applied impulses in a known manner for ensuring that only positive impulses are allowed to pass to the ring valves 1, 2 and 3. Positive impulses at L1 produce positive impulses at the cathode of valve 4, which is connected via condensers 10, 20, 30 to the grids of valves 1, 2 and 3, respectively, via their grid resistors 14, 24, and 34 respectively.

Valve 5 with its cathode resistor 51, grid resistors 52 and 53 to produce negative bias and condenser 54 connecting its grid to the anode of valve 1, serves in the manner of valve 4 to pass positive impulses to the output lead L2 and along this lead to drive the next scale of the counter or to operate indicating or integrating devices of known character, not shown.

The usual means of heating the valve cathodes is employed but is not shown.

By suitably choosing the resistance, condenser and battery voltage values, valves 1, 2 and 3 are arranged to have three stable conditions corresponding to the three combinations in which one of the valves has its anode current cut off and the remaining two are fully conducting, that is, their control grids are passing grid current. Each impulse impressed on lead L1, provided that there is a certain minimum interval between the impulses, causes the cut-off condition to be transferred to the next valve in the given sequence, which in the present case is 1, 2, 3, 1, 2, 3, etc.

The cut-off condition of valve 1 corresponds to zero on the counter scale. The scale may be set to zero before a count by connecting the screen grid of valve 1 to a potential negative to earth by means not shown or may be so set by other known means. Each time the anode current of valve 1 is cut-off during a count, an impulse is passed by way of valve 5 to the next counter scale via lead L2.

To trace the transition from one to another stable condition assume that valve 1 is non-conducting and valves 2 and 3 are both conducting before an impulse is received on lead L1 and that sufficient time has elapsed since the last impulse for substantially steady state conditions to have been reached by voltages on the sundry condensers. A positive impulse of sufficient magnitude applied to lead L1 will cause the cathode of valve 4 to apply a positive pulse to each of the condensers 10, 20, 30. This pulse will be communicated to the control grid circuit of each valve 1, 2, 3. It will produce no effect on valves 2 and 3 because these valves are already passing grid current but valve 1 will become conducting and will be maintained conducting by the D. C. feed-

back from valve 2, the anode of which is rendered non-conducting as next described. The potential of the anode of valve 1 becoming less positive acts via condenser 26 and resistors 27, 28 to impress 5 a negative voltage impulse on the suppressor grid of valve 2 and thus render the anode of valve 2 non-conducting by diverting the cathode emission from the anode to the screen grid. The resistors 19, 29, 39, in series with the screen grids 10 of valves 1, 2, 3 are desirable to protect the screen grids from excessive currents under this condition. The anode of valve 2 remains non-conducting provided that during the attainment of steady state conditions by the condensers the negative suppressor grid voltage remains effective until the reduced D. C. feed-back to valve 2 lowers the voltage of the grid to a value such as would normally reduce the anode current to zero. This condition is easily satisfied by suitable choice of 15 condenser sizes. The change of anode potential of valve 2 tends to make the suppressor grid of valve 3 positive with respect to its cathode but this has negligible effect on the anode of valve 3. It is essential for reliable operation that the grid 20 potential of a valve which has not changed its anode condition should remain substantially constant as otherwise undesirable variations in anode potential are produced. In the change of stable 25 condition being described the condition of electron flow in valve 3 does not have to change but the pulse applied to lead L1 makes the plate of condenser 30 nearer the grid of valve 3 first of all positive and then negative with respect to the steady state condition. The anode current of 30 valve 3 is made to remain substantially constant 35 under these conditions by arranging that the common connection of resistors 32, 33, 35 and condenser 30 is always during these conditions at a potential positive to that control grid potential of 40 valve 3 at which grid current commences to flow. The resistor 34 then allows the control grid potential to remain substantially constant. The voltages at the common connection of the resistors 12, 45 13 and 15 and condensers 10 and the common connection of the resistors 22, 23 and 25 and condenser 20 are similarly determined at the appropriate times.

It will be appreciated that in any impulse counter of the type defined the anodes of each 50 valve in the counting ring will at the instant of application of an impulse be simultaneously under the influence of the impulse, the D. C. and the A. C. feed-backs to that valve. These influences may be contrary in their effects on the 55 anode current of a particular valve and thus tend to render the desired change of anode condition uncertain in its early stages. By applying the D. C. and A. C. feed-backs according to the invention to different grids of a multi-grid valve 60 uncertainty as to anode change of potential is eliminated. In the example shown in the drawing and described in the foregoing the A. C. feed-back by applying negative voltage to the suppressor grid cuts the anode current off independently of the impulse and D. C. feed-back 65 voltages, and thus produces a clean change over from the conducting to non-conducting condition. It will be appreciated that the invention can be applied to a ring or scale of any number. 70 In a particular application in which scale-of-five units were required to count at a maximum rate of 2500 pulses per second, the following circuit elements were found to work reliably, the component numbers being read in conjunction 75 with the diagram.

Condenser 44, 54—0.001 microfarad.
 Resistor 42, 52—100,000 ohms.
 Resistor 43, 53—470,000 ohms.
 Resistor 41, 51—4,700 ohms.
 Valve 4 and 5—L63.
 Anode resistors 11, 21 etc.—33,000 ohms.
 Screen grid resistors 19, 29 etc.—10,000 ohms.
 D. C. feed-back resistors 12, 13 etc.—1 megohm.
 Resistors 15, 25 etc.—1 megohm.
 Condensers 10, 28 etc.—0.00005 microfarad.
 Condensers 16, 26 etc.—0.0001 microfarad.
 Resistors 17, 27 etc.—220,000 ohms.
 Resistors 18, 28 etc.—220,000 ohms.
 Battery V1—100 volts.
 Battery V2—90 volts.
 Ring valves 1, 2, 3, 4 and 5—EF 36.

I claim:

1. Electronic valve apparatus for counting electrical impulses having input and output circuits, a plurality of electronic valves each having a plurality of electrodes including a plurality of grids and arranged in a ring formation with a load device in the output circuit of each valve, means responsive to successive electrical impulses at the input circuit for making each valve in turn non-conducting while the other valves are conducting, said means comprising a circuit arrangement connecting an electrode of each valve with one of the grids of each of the other valves for applying a direct current voltage produced at the said electrode to each of said grids and a circuit arrangement connecting an electrode of each valve with a grid of the next succeeding valve in the ring formation other than the grid of said next succeeding valve to which the said direct current voltage is applied, said last mentioned arrangement being arranged to apply a transient voltage produced at said electrode to said other grid to make said next succeeding valve non-conducting.

2. Electronic valve apparatus for counting electrical impulses having input and output circuits, a plurality of electronic valves each having a plurality of electrodes including a plurality of grids and arranged in a ring formation with a load device in the output circuit of each valve, and means responsive to successive electrical impulses at the input circuit for making each valve in turn non-conducting while the other valves are conducting, said means including circuit connections for simultaneously applying electrical impulses at the input circuit to a grid of each valve whereby the non-conducting valve in the ring formation is caused to conduct, a circuit connecting means connecting an electrode of each valve with the same grid of each of the other valves for applying a direct current voltage to the respective grids, and a circuit arrangement connecting an electrode of each valve with a different grid of the next succeeding valve in ring formation for applying a transient voltage produced at the electrode to said different grid to make the adjacent valve nonconducting.

3. Electronic valve apparatus for counting elec-

trical impulses having input and output circuits, a plurality of electronic valves each having a plurality of electrodes comprising a plurality of grids including a control grid and a suppressor grid and arranged in a ring formation with a load device in the output circuit of each valve, and means responsive to successive electrical impulses at the input circuit for making each valve in turn non-conducting while the other valves are conducting, said means comprising a circuit arrangement connecting an electrode of each valve with the control grid of each of the other valves for applying a direct current voltage produced at the electrode to each of said control grids, a circuit arrangement connecting the input circuit with each of said control grids for applying an impulse from said input circuit to each of said control grids, and a circuit arrangement connecting an electrode of each valve with the suppressor grid of the next succeeding valve in the ring formation for applying a transient voltage produced at the electrode to said suppressor grid to make said next succeeding valve non-conducting.

4. Electronic valve apparatus for counting electrical impulses having input and output circuits, a plurality of electronic valves arranged in a ring formation and each having an anode and a plurality of grids including a control grid and a suppressor grid, each said valve having a conducting and non-conducting condition of stability and means responsive to successive electrical impulses at the input circuit for changing the condition of stability of each valve in turn, said means comprising a circuit arrangement connecting an anode of each valve with the control grid of each of the other valves in the ring formation for applying a direct current voltage produced at the said anode to each said control grid, a circuit arrangement connecting the input circuit with each of said control grids for applying an impulse from said input circuit to each of said control grids, and a circuit arrangement connecting an anode of each valve with the suppressor grid of the next succeeding valve in the ring formation for applying a transient voltage produced at said anode to said suppressor grid to make said next succeeding valve non-conducting.
